E. FISK & J. C. GREEN.
ANTIFRICTION BOX FOR HUBS AND ROTARY BEARINGS OF MACHINERY.
Patented Nov. 14, 1835.

Ezra Fisher and Joseph C. Green

697

The substance referred to in these Letters Patent and making part of the same containing a description in the words of the said Ezra Fisher and Joseph C. Green themselves of their improvement in the construction box for Hubs and Rotary bearings of Machinery.

To all to whom these presents shall come,

Be it known that we Ezra Fisher and Joseph C. Green both of Fayette in the County of Penobscot and State of Maine have invented a new and useful construction box to be applied and used in the hubs of carriage wheels, and in the rotary bearings of machinery and that the following is a full and exact description of the construction and operation of said box as invented by us.

The combination of friction rollers say eight in number constitute the bases of this box, the size of the rollers may be various according to their application and use. There are four primary rollers of equal diameters which are placed in the four quarter sections of a circle leaving a central space between them, sufficient to accommodate the size of the axle or shaft which is designed to work in the box. There are also four secondary rollers of equal diameters the diameters varying so as to adapt them to the size of the primary rollers. These occupy the spaces between the primary rollers, and their horizontal thickness must be equal that of the primary sufficient to receive a metallic ring or collar on each side of the primary rollers. The secondary rollers and collars are connected by making grooves on the periphery of the rollers corresponding to the horizontal thickness of the collars. To prevent the collars from coming in contact with the sides of the primary rollers, the space between the grooves on the secondary rollers must be equal the horizontal thickness of the primary, about one eighth of an inch, and to prevent any

any horizontal movement of the secondary rollers, suitable tongues are made on their peripheries at the centre of their horizontal thickness, fitted to work in corresponding grooves in the periphery of the primary rollers. This combination of rollers is enclosed by a metallic hoop of sufficient ^{strength} having regard to the pressure it has to be sustained.

On each side of the combination of rollers is a circular piece of plate of some suitable kind of metal exactly fitted to the inside of enclosing hoop and confined to their places by any suitable kind of fastening. Thus these plates at the centre, are round perforations the diameter of which must exceed that of the axle or shaft about one fourth of an inch, in the inner surface of the enclosing hoop is a groove one eighth of an inch deep ~~the width~~ responding to the horizontal thickness of the primary rollers, the edges of which work in the groove. When a shaft is inserted in the box the primary rollers have a peripheral bearing both on the axle and the enclosing hoop. The secondary rollers have also a peripheral bearing both on the curvature of the collars and the periphery of the primary rollers. The space between the plates and the rollers should be one eighth of an inch on each side. All the component parts of the box should be made of some suitable kind of metal having regard to the degree of strength and elegance required. When the size of the axle and the enclosing hoop are determined, the diameter of the primary rollers must be such as precisely fill the space between the axle and the enclosing hoop. The secondary rollers must not be large as to bring their collars in contact with the enclosing hoop. The foregoing is a general description both of the exterior and interior structure of the box, we have stated no specific materials to be employed in its construction.

(234)

tion, for they may be various according as fancy or judgment shall dictate, and we have given no specific dimensions of the component parts of the box, for they must necessarily be various, according to the application, and use of the box.

The above specific method of combining the roller is such that in this application and use, all the bearings are spherical, consequently the operation of all the parts is entirely on the roller principle. To relieve friction on the shoulder of the axle, at the inward end of the hub a metallic collar is fitted on the axle with a groove in that side of which comes in contact with the collar, by placing in the groove a ball of some suitable kind of hard metal, if like collar and ball is fitted on the axle tree at the outward end of the hub, these collars with the balls are not considered as a necessary appendage of the box, the box may be used with or without them at pleasure.

In the application of the above specific anti-friction box to the wheels of a single horse --- wagon or chaise the following dimensions are considered convenient. The enclosing hoop may be made of cast iron or any suitable composition of metals for inches diameter inside and of suitable thickness say half an inch, and about four inches in width. The plate or side of the box which comes next to the hub, should be cast with the hoop.

The extension of the hoop on the hub may be one inch and its thickness at its termination on the hub may be reduced to one fourth of an inch. Circular perforations half an inch diameter are made thru the plate at the four quarter sections of a circle about half an inch from the inside of the hoop and corresponding perforations are made through the length of the hub. The box is confined to each end of the hub by sufficient

iron bolts thro' the perforations in the plates and hub, with heads on one end of the bolts. Concrete blocks in the plate of the inside box, and a screw on the other end of the bolts, fitted to screw into the perforations made in the plate of the outside box. The diameter of the box attached to the outward end of the hub may be about three fourths of an inch less than the box on the inward end of the hub. To render the connection between the box and hub more permanent, there are on the side of the plates which come in contact with the ends of the hub, and in the intervening spaces between the above described perforations, projections one inch in length and half an inch rise the projections being fitted into corresponding excavations made in the ends of the hub on lines drawn from the circumference towards the centre. The diameter of the axle for a hub, ^{of iron} stated dimensions may be one inch and three fourths, — the diameter of the primary rollers will then be about one inch and five eighths, and the diameter of the secondary rollers about one and one eighth. The collars which enclose the secondary rollers may be one fourth of an inch thick each way. The box on the outward end of the hub being three fourths of an inch (or more at pleasure) less than the box on the inward end of the hub, the outward end of the axle will be proportionately smaller that at the shoulder.

The collar which forms the shoulder of the axle of the hub and encloses a friction ball, may project about one inch from the surface of the axle and the ball may be half an inch diameter, the collar and ball at the other end of the hub must be proportionately smaller. To prepare the above described box to be used as a bearing for any rotary shaft, it is only necessary to make such additions to the enclosing box as will answer the purpose for fastening according to the

ring and using the collar on the cycle or staff together
with the balls
